UNITED STATES PATENT OFFICE.

WILLIE J. TOWER, OF SEATTLE, WASHINGTON.

ROTARY VALVE.

1,215,746.

Specification of Letters Patent. Patented Feb. 13, 1917.

Application filed December 22, 1915. Serial No. 68,283.

To all whom it may concern:

Be it known that I, WILLIE J. TOWER, citizen of the United States, residing at Seattle, in the county of King and State of Washington, have invented a certain new and useful Improvement in Rotary Valves, of which the following is a specification.

My invention relates to improvements in rotary valves of internal combustion engines, and the object of my invention is to provide a duplex rotary valve of simple form which may be embodied in an internal combustion engine and which shall be adapted efficiently to operate to control both the intake port and the exhaust port of a cylinder of said engine.

I accomplish this object by devices illustrated in the accompanying drawings wherein Figure 1 is a view in a side elevation of portions of an internal combustion engine embodying my invention, some parts of which are shown in vertical mid-section; Fig. 2 is a fragmentary view showing parts of the same in another side elevation; Fig. 3 is a fragmentary view of the same in vertical section on broken line y, y of Fig. 1; Fig. 4 is a fragmentary view of the same in vertical section on broken line x, x of Fig. 1; and Fig. 5 is a fragmentary view in side elevation of the same, showing details thereof.

In the drawings, throughout which like reference numerals indicate like parts, I have illustrated an internal combustion engine wherein 6 is a crank case upon which is secured the lower end of a cylinder 7 which is provided with a water jacket 8 integral therewith, and which is further provided with an integral valve-socket 9 on one side of its top wall 10, as more clearly shown in Fig. 3, said valve-socket 9 being surrounded by said water jacket 8.

Within the valve-socket 9 is rotatably disposed a closely fitting rotary valve 11 on one end of which is disposed an integral journal 12 that fits a bearing that extends through one end of said valve-socket 9, and said journal 12 is provided with an extended portion 13 of smaller diameter upon which portion 13 is fastened a spur wheel 14 having twelve teeth, as teeth 15, shown more clearly in Fig. 2, which teeth 15 are adapted to engage with a worm-like cam 16 which

is fastened on a shaft 17 that is disposed with its axis at a right angle to the axis of the rotary valve 11, and which shaft 17 is rotatably mounted in suitable bearings not shown.

Mounted securely on one end of the shaft 17 is a beveled gearwheel 18 which engages with a like beveled gearwheel 19 that is fastened on the upper end of a shaft 20 which is disposed to be rotatable in bearing brackets 21 and 22 (the bearing bracket 21 being fastened to the water jacket 8 65 while the bearing bracket 22 is fastened to one end of the crank case 1), and on the lower end of said shaft 20 is fastened a beveled gearwheel 23 which is disposed to engage with a beveled gearwheel 24 that is mounted securely on the crank shaft 25 of the engine, said gearwheel 24 having twice as many teeth as the gearwheel 23 whereby the shafts 20 and 17 will each revolve twice in response to one revolution of the crank shaft 25.

The worm-like cam 16 is provided with a worm thread 26 whose two convolutions (as shown in Fig. 2) are formed and disposed so that for the greater portion of 80 their circular distances their side surfaces, which engage successively with the teeth 15, are in vertical planes that are at right angles to the axis of the shaft 17 whereby as said worm-like cam 16 rotatively moves 85 throughout such circular distance the spur wheel 14 will remain at rest, but throughout the remaining smaller portion of the circular distances their side surfaces are spirally disposed to form cams, as cams 27, 90 so that as said spirally disposed side surfaces of said cams 27 rotatively move to engage with and pass successive ones of the teeth 15 the spur wheel 14 will be rotatively moved through an angular distance of one 95 of its teeth.

Thus, a continuous rotation of the shaft 17, in response to revolutions of the crank shaft 25, will cause intermittent rotative movements of the spur wheel 14, one of 100 which movements will occur for each revolution of said shaft 17, and such intermittent rotative movements will be communicated to the rotary valve 11.

It is manifest, therefore, that each revolution of the crank shaft 25 will cause the

rotary valve 11 rotatively to move at two separate times, each time through an angular distance of thirty degrees.

The other end of the valve socket 9 is provided with an internal screw-thread which engages with the external screw-thread of an elbow 28 to which is connected an exhaust pipe 29, and near the inner end surface of said elbow 28 is an inlet passageway 30, for an explosive mixture of fuel and air, which extends upwardly through the walls of the water jacket 8 and the valve socket 9, as shown more clearly in Fig. 1.

The rotary valve 11 is provided with a centrally disposed longitudinal chamber 31, which opens into the elbow 28, and is further provided with three concentrically disposed longitudinal chambers 32 whose cross-sectional shape is like a segment of a circle and which are placed equi-distant one from another, as more clearly shown in Figs. 3 and 4, and through the metal between adjacent ones of all three of said chambers 32 is a passageway, as passageways 33, 25 which extends from the chamber 31 to the periphery of said rotary valve 11; and also extending from each of the several chambers 32 to the periphery of said rotary valve 11 at corresponding points thereof is a passageway, as passageway 34.

On the end portion of the rotary valve 11, in a position registering with the inlet passageway 30, there is formed an annular recess 35 which communicates with said inlet passageway 30 and with all of the chambers 32 whereby at all times an explosive mixture may pass from said inlet passageway 30 to said chambers 32.

As shown more clearly in Fig. 3 there is a passageway 36 that extends from the inner surface of the valve socket 9 through the top wall 10 into the interior of the cylinder 7, the form of said passageway 36 corresponding to the form of the several passageways 33 and 34 whereby during the operation of the engine said passageways 33 and 34 will alternately register with said passageway 36 with the result that the interior of the cylinder 7 will alternately be in communication with the exhaust pipe 29 and the inlet passageway 30.

The relative circumferential positions of the worm-like cam 16, the spur wheel 14, the rotary valve 11 and the crank shaft 25 must be such as will, at required instants of time cause a required one of the passageways 33 and 34 to move to the position opposite the passageway 36 there to rest for such length of time as will permit respectively the emission of products of combustion from the cylinder 7 and the admission of an explosive mixture thereinto in an obvious manner.

In order to ignite an explosive mixture within the upper portion of the cylinder 7 I have provided a spark plug 37 of well

known form which is disposed to extend through the top wall 10 of said cylinder 7 which spark plug 37 may be associated with well known electrical circuits and apparatus not shown whereby sparks may be caused to jump from one of its electrodes to the other, and in order that such sparks may be controlled to occur at proper instants of time with respect to the varying positions of the rotary valve 11 I have provided one form of means for causing such sparks to occur only at such proper instants of time, which means include an insulated contact point 38, secured to the top portion of the cylinder 7, in which position it is adapted to be engaged by a contact point 39 that is fixed on one end of a lever 40 that is pivotally fulcrumed on a stud 41 that is fixed in a lug 42 that projects from the top portion of the wall of the water jacket 8, the other end of said lever 40 being disposed in the path of three cam-like projections 43 which are integral with the periphery of a disk 44 which is attached to the outer side of the spur wheel 14 to be adjustably movable to desired different circumferential points thereon, whereby the contact points 38 and 39 may be caused to make and break contact with each other at required times with respect to the different circumferential positions of the rotary valve 11, said contact points 38 and 39 being connected with circuits, not shown, which are associated in a well known manner with the spark plug 37 and the spark producing apparatus.

Associated with the lever 40 is a flat spring 45 which is adapted normally to keep the contact point 39 disengaged from the contact point 38.

One skilled in the art will readily understand the plan of construction and mode of operation of my invention upon reading the description of my invention hereinbefore given in connection with the accompanying drawings.

It is manifest that two separate rotary valves for the same cylinder may be substituted for the duplex rotary valve 11; in which case each of said two rotary valves would embody only one chamber having three equi-distantly disposed passageways through its walls which passageways would be moved successively to register with the respective one of two passageways that would be formed to extend from the interior of the cylinder each to a different one of the valve sockets of said two rotary valves, one of which passageways would serve as an intake port while the other would serve as an exhaust port in an obvious manner.

Manifestly, the circuit controlling device which includes the contact points 38 and 39, and the lever 40 together with the disk 44 may be properly associated with suitable mechanism and other moving parts of the

engine instead of being directly associated with the spur wheel 14, and other changes in the forms, dimensions and arrangement of parts of my invention without departing 5 from the spirit thereof.

What I claim is:

An internal combustion engine comprising a cylinder having an offset valve casing carried thereby, a rotary valve mounted in 10 said casing, said valve including concentric cylinders closed at one end by an integral right-angularly extending wall, the opposite end of the outer cylinder terminating inwardly of the outer end of the inner cylinder, an annular peripheral collar carried by 15 the inner cylinder adjacent the open end with the outer edge lying in the same plane as the outer edge of the outer cylinder, radial connecting members between the cyl-

inders dividing the space between the cylinders into non-communicating chambers, ports extending through said connecting members from the interior of the inner cylinder to the exterior of the outer cylinder constituting an exhaust passage, and ports 20 in the outer cylinder communicating with the chambers constituting gas inlets, a combined inlet and exhaust port in the engine cylinder adapted successively to register with the valve ports, and means for rotating 25 the valve.

In witness whereof, I hereunto subscribe my name this seventh day of December, A. D. 1915.

WILLIE J. TOWER.
